UNITED STATES PATENT OFFICE.

MARTIN F. BURNS, OF FLUSHING, NEW YORK.

DENTAL CASTING MACHINE.

Application filed November 21, 1922. Serial No. 602,448.

To all whom it may concern:

Be it known that I, MARTIN F. BURNS, a citizen of the United States, and a resident of Flushing, county of Queens, and State of New York, have invented certain new and useful Improvements in Dental Casting Machines, of which the following is a specification.

The invention relates to dental casting machines used for casting plates, bridges, inlays and other restorations.

In casting a plate, bridge or other restoration, a dentist first makes a pattern in wax of the article to be cast. The pattern is then placed in an investment holder and is melted out or otherwise dissipated and the cavity is filled with molten metal. The metal is forced into the cavity under pressure to effect the complete filling of the cavity. The casting is then allowed to cool and is preferably cooled slowly to prevent warping or distortion.

The pressure utilized in the casting process is usually derived from compressed air and in casting machines now in use this compressed air is taken from air tanks or compressed air systems.

This invention has for its salient object to provide a simple, practical, inexpensive and self-contained dental casting unit or apparatus so constructed that the air is compressed by the apparatus during the operation thereof.

Another object of the invention is to provide apparatus of the class described having its operative parts adjustable to a plurality of working positions whereby the degree of compression of the air therein can be varied.

Further objects of the invention will appear from the following description taken in connection with the drawings which form a part of this application and in which,

Fig. 1 is a sectional elevation of one form of apparatus constructed in accordance with the invention, the base and member adapted to telescope thereon being shown in separated position.

Fig. 2 is a view similar to Fig. 1 but showing the parts in operative position, the upper member being telescoped on the base.

Fig. 3 is a detail sectional view taken substantially on line 3-3 of Fig. 2.

Fig. 4 is a top plan view of one of the supporting members for the dental flask.

Fig. 5 is a sectional elevation similar to Fig. 2 but showing another form of the apparatus.

The invention briefly described comprises a base having means for supporting a dental flask and a member adapted to telescope on said base and to compress air between the member and the base as the member is moved to telescoping position. Means are also provided for directing the compressed air to the flask and for sealing the parts so as to confine the air and to direct it into the flask. Further details of the invention will appear from the following description.

The apparatus comprises a base 10 having a substantially cylindrical member 11 mounted thereon, the member 11 having an upper supporting surface 12 extending transversely thereof. The surface 12 in turn carries or has formed integrally therewith and disposed centrally with reference thereto, a receptacle 13 having a plurality of sets of vertically spaced supporting lugs 14 extending inwardly from the inner surface thereof. The lugs 14 are adapted to support members 15 which in turn support the dental flask.

The members 15 are substantially cylindrical in shape and have flanges 16 extending laterally from the upper edges thereof. As illustrated in Figs. 1, 2 and 5 a plurality of these flask supporting members is provided, these members having different dimensions or being of different depth so that the flask may be supported at different levels in the base of the casting machine. Each of the members 15 has formed in the flange 16 thereof notches 17 so formed that the lugs 14 will pass through these notches in case it is desired to support the member 15 on the lower set of lugs 14. Each of the flask supports 15 also has formed therein a plurality of perforations 18 for permitting the passage of air therethrough during the casting process. With two flask supporting members 15 of different dimension, as shown in Fig. 1, it will be obvious that the dental flask may be supported at a plurality of different levels since each supporting member may be supported on either set of lugs and each supporting member may be reversed as shown in the dot and dash lines shown in Fig. 1.

The dental flask may be of any form or shape desired and that illustrated in the

drawings comprises an outer receptacle 19 and an investment holder 20 supported thereon and disposed therein. The drawings also illustrate the investment 21 in the investment holder, a cavity 22 to be filled with metal during the casting and the molten metal 23 disposed in a concave depression 24 in the investment. The metal may be heated in any desired manner as by a blow pipe 25.

If desired the receptacle 13 may have heating means therein such as heating coils 13' for the purpose of heating the investment and wax pattern and dissipating the 15 wax.

A plurality of upright standards 26 is secured to the base 10 and a member 27 is slidably supported at 28 on the standards 26 and is adapted to telescope on the cylindrical portion 11 of the base. During the telescoping operation the air is compressed in the bell shaped member 27 and it is therefore desirable that the member 27 fit closely on the outer surface of the portion 11 of 25 the base to prevent the air from escaping therebetween. This may be accomplished in any desired manner and in the form of the invention illustrated a flexible washer 29 formed of any suitable material such as 30 leather is secured to the lower headed end of the member 27 by a flange 30 formed on a sleeve 31 which is threaded on the lower end of the member 27. As the member 27 is telescoped on the portion 11 of the base 35 this washer is bent upwardly as shown in Fig. 2 thereby forming a seal.

Means are provided for directing the air compressed within the bell shaped member 27 to the dental flask and for confining the 40 air during the casting operation. The bell shaped member 27 is provided with a transverse member 32 in its upper portion, this member having a downwardly extending centrally disposed sleeve 33 formed thereon. The sleeve 33 is provided at its lower end with a laterally extending flange 34. The member 32 has also formed therein a plurality of openings 35 for permitting the air to pass upwardly into the dome 36 of the 50 bell shaped member 27.

An elongated tubular member 38 is slidably mounted in the sleeve 33, the downward movement of this member being limited by a flange 39 formed on the upper 55 end of the member 38 and engageable with the upper surface of the member 32.

The tubular member 38 has formed on its lower end a V-shaped groove or sealing ring 40 adapted, as shown in Fig. 2, to fit 60 on the upper edge of the dental flask or of the investment holder 20 thereby confining the air to the flask.

In order to increase the velocity of the air as it is directed into the flask a perforated 65 thimble 41 is supported by a collar 42 in

the tubular member 38, this thimble being disposed directly above the concave depression 24 in the investment when the parts are moved to the operative position as shown in Fig. 2.

Further means is provided for sealing the parts and for confining the air, this means comprising a bell shaped member 43 secured as shown at 44 to the outer surface of the tubular member 38 and having its lower 75 edge 45 adapted to enter a groove 46 formed in the surface 12.

The tubular member and the parts carried thereby are normally urged in a downward direction by a spring 47 which engages at 80 its lower end a flange 48 formed on the member 43 and at its upper end the flange 49 formed on the sleeve 33. As above stated the downward movement of the tubular member 38 is limited by the flange 49 formed thereon.

A gauge 50 is mounted on the member 27 to indicate the air pressure therein.

Any suitable means may be used for operating the bell shaped telescoping member 90 27 and in the embodiments of the invention illustrated this member has a rod 51 secured to the dome 36 thereof and extending upwardly therefrom. This rod passes through a guide 52 carried by the upright standards 95 26 and means is provided on the guide 52 for retaining the member 27 in elevated position. This retaining means consists of balls 53 resiliently actuated by springs 54 and engageable with notches or depressions 100 55 formed in the rod 51. As the member 27 is raised therefore the balls 53 will be forced into the depressions 55 thereby resiliently retaining the member 27 in elevated 105 position.

The actuating means for the telescoping member consists of a lever 60 having a slot 61 in which is disposed a pin 62 carried by the rod 51. The lever 60 is fulcrumed on an adjustable pivot pin 63 carried by a collar 64 carried by a sleeve 65 which in turn is threaded on the upper end of one of the standards 26. Handles 66 are formed on the sleeve for facilitating the rotation thereof.

As shown in Fig. 3 the lever 60 comprises a pair of bars 67 each of these bars having a pin and slot connection with the pin 62 and each of the bars being pivoted at 63 to the collar 64.

Means is provided for latching the lever after it has been depressed and this means is shown in detail in Fig. 3. The latching means consists of a pair of latching pawls 68 pivoted on a common pivot 69 on one of the standards 26. A spring 70 is interposed between the pawls and normally forces them outwardly, this movement being limited by lugs 71 formed on the lower ends of the pawls and engageable with stops 72 formed 125 130

in the standard 26. When the lever is depressed the straps or bars 67 can pass downwardly over the latches until they engage a cross pin or stop 73 on the standard 26 and when the bars reach this position the pawls 68 will snap outwardly retaining the lever in this position. If further adjustment of the telescoping member is desired the lever fulcrum can be depressed by rotating the sleeve 65.

Since as above stated it is very desirable to have a close fit between the telescoping member 27 and the portion 11 of the base, the portion 11 is protected by a cylindrical casing 74 secured to the base and surrounding the outer finished surface of the base portion 11.

The apparatus above described operates in the following manner. When the pattern has been invested in the investment and the wax has been dissipated the flask is placed in the casting machine and the gold or other metal is melted in the cavity 24 in the investment. The blow pipe or other heating means is then withdrawn and the operator will depress the telescoping member 27 to the position shown in Fig. 2 by exerting force on the lever 60. During this telescoping of the member 27 on the base portion 11, the tubular member 38 will be also depressed and the spring 47 will force the edge 45 of the member 43 into sealing engagement with the groove 46 on the surface 12 of the base and will also force the sealing groove 40 on the lower end of the tubular member 38 into sealing engagement with the upper edge of the investment holder 20. Furthermore during this telescoping action or depression of the bell shaped member 27, air will be trapped therein and will pass upwardly through the openings 35 and subsequently downwardly through the air directing member 38 and through the thimble 41 into the flask thereby forcing the gold into the cavity and forming a perfect casting. As the air is forced downwardly into the flask it may escape through the constricted openings 18 in the flask supporting member 15.

Attention is called to the fact that the air compressed and forced into the flask is warm air since it has been heated by the blow pipes. The lever and fulcrum adjusting member may be operated in such a manner as to apply the pressure gradually and to maintain a uniform pressure after the desired pressure has been reached.

The form of the invention illustrated in Fig. 5 differs from that already described in that the apparatus shown therein has supplemental air compressing means. The base, bell shaped telescoping member and operating parts are substantially the same as those shown in the preceding figures and therefore corresponding numbers have been used to indicate like parts.

In the embodiment of the invention shown in Fig. 5 however the rod 81 which corresponds to the rod 51 in Figs. 1 and 2 is not secured to the dome 36 of the bell shaped telescoping member 27. This rod in this instance is secured to a piston 82 and passes through an opening 83 in the dome 36 and a packing 84 prevents escape of the air through the opening. The piston 82 has formed thereon a downwardly extending sleeve 85 positioned in the tubular member 38 and this sleeve has formed therein a plurality of openings 86 for the admission of air to the interior of the sleeve.

The rod 81 is preferably hollow or longitudinally bored and a gauge 88 communicates with the upper portion of the rod and indicates the air pressure in the member 38.

In this form of the invention a compression spring 89 is mounted on each of the standards 26 and is disposed between the lugs 28 carried by the member 27 and the transverse guiding member 52. These springs normally urge the telescoping member 27 in a downward direction.

The device shown in Fig. 5 operates in the following manner. As the lever 60 is depressed the rod 81 is released from the balls 53. The springs 89 will force the member 27 downwardly and the spring 47 will force the tubular member 38 into sealing position as shown in Fig. 2 and as described in connection with the other embodiment of the invention. As the member 27 is forced downwardly and telescopes over the base portion 11 air is compressed in the bell shaped member 27 and passes upwardly through the openings 35 and inwardly through the openings 86 to the interior of the piston sleeve 35. The air then passes downwardly through the air directing tubular member 38 and into the flask as with the other embodiment. When the member 27 has reached the position shown in Fig. 5 further depression of the rod 80 will cause the piston 82 to move downwardly in the tubular member 38 closing the openings 86 and trapping the air in the member 38. This operation will therefore further compress the air and force the air into the flask.

It will be seen from the foregoing specification that a single operation namely, the operation of the lever, will effect the compression of the air and the direction of this compressed air to the dental flask and furthermore that this same operation will seal the parts in such a manner that the air will be confined and will effectively perform its function.

Although certain specific embodiments of the invention have been particularly illustrated and described it will be understood that the invention is capable of further modification and that further changes in the construction and in the arrangement of the

various cooperating parts may be made without departing from the spirit or scope of the invention as expressed in the following claims.

5. What I claim is:—

1. A dental casting machine comprising a pair of telescoping members, one of said members having a support for a dental flask and the other member having means for directing the air to said flask as said members are moved into telescoping relation and the air is compressed between the members.

10. A dental casting machine comprising a pair of telescoping members, one of said members having an adjustable support for a dental flask and the other member having means for directing the air to said flask as said members are moved into telescoping relation and the air is compressed between the members.

15. A dental casting machine comprising a pair of substantially cylindrical telescoping members, one of said members having a support for a dental flask and the other member having means for directing the air to said flask as said members are moved into telescoping relation and the air is compressed between the members.

20. A dental casting machine comprising a pair of telescoping members, one of said members having a support for a dental flask and the other member having means for directing the air to said flask as said members are moved into telescoping relation and the air is compressed between the members, means for holding one of said members in a position spaced from the other member and means for latching said members in telescoping position.

25. A dental casting machine comprising a pair of telescoping members, one of said members having a support for a dental flask and the other member having means for directing the air to said flask as said members are moved into telescoping relation and the air is compressed between the members, and means including a lever for moving one of said members into telescoping position on the other member.

30. A dental casting machine comprising a pair of telescoping members, one of said members having a support for a dental flask and the other member having means for directing the air to said flask as said members are moved into telescoping relation and the air is compressed between the members, means including a lever for moving one of said members into telescoping position on the other member, and means for adjusting the fulcrum of said lever.

35. A dental casting machine comprising a pair of telescoping members, one of said members having a plurality of adjustable supports for a dental flask and the other member having means for directing the

air to said flask as said members are moved into telescoping relation and the air is compressed between the members.

8. A dental casting machine comprising a base having a support for a dental flask, a member adapted to telescope on said base and means slidably carried by and positioned within said member for directing air into said flask as said member is moved to telescoping position on said base.

75. 9. A dental casting machine comprising a base having a support for a dental flask, a member adapted to closely fit and telescope on said base and means slidably carried by and positioned within said member for directing air into said flask as said member is moved to telescoping position on said base.

80. 10. A dental casting machine comprising a base having a support for a dental flask, a member adapted to telescope on said base, means slidably carried by and positioned within said member for directing air into said flask as said member is moved to telescoping position on said base, and resilient means tending to separate said means from said member.

85. 11. A dental casting machine comprising a base having a support for a dental flask, a member adapted to telescope on said base and means slidably carried by and positioned within said member for directing air into said flask as said member is moved to telescoping position on said base, said slidable means having sealing means adapted to surround the flask and confine air therein.

90. 12. A dental casting machine comprising a base having a support for a dental flask, a member adapted to telescope on said base and means slidably carried by and positioned within said member for directing air into said flask as said member is moved to telescoping position on said base, said slidable means having sealing means adapted to engage the flask and confine air therein.

95. 13. A dental casting machine comprising a base having a support for a dental flask, a member adapted to telescope on said base and means slidably carried by and positioned within said member for directing air into said flask as said member is moved to telescoping position on said base, said slid- 100 able means having a plurality of sealing means adapted to confine air in the flask as the air is directed thereto.

105. 14. A dental casting machine comprising a base having a support for a dental flask, a member adapted to telescope on said base and means slidably carried by and positioned within said member for directing air into said flask as said member is moved to telescoping position on said base, said slidable means having annular sealing 110 115 120 125 130

means adapted to surround the flask and confine air therein. 65

15. A dental casting machine comprising

a base having a support for a dental flask, a member adapted to telescope on said base

and means slidably carried by and positioned within said member for directing air into said flask as said member is moved to telescoping position on said base, said

10 said slideable means having a plurality of annular sealing means adapted to confine air in the

flask as the air is directed thereto. 70

16. A dental casting machine comprising

a base having a support for a dental flask, a member adapted to telescope on said base and

means slidably carried by and positioned within said member for directing air into

said flask as said member is moved to tele-

scoping position on said base, said slideable

20 means having sealing means adapted to sur-

round the flask and confine air therein, and

resilient means for forcing said sealing

means into sealing position as said member

is moved to telescoping position on said base. 75

25 17. A dental casting machine comprising

a base having a supporting member ex-

tending transversely thereof, means carried

by said member for supporting a dental flask, a member adapted to closely fit and

30 telescope on said base and to compress air

therebetween, and means carried by said

telescoping member for directing the com-

pressed air into said flask. 90

18. A dental casting machine comprising

35 a base having a supporting member extend-

ing transversely thereof, means carried by

said member for supporting a dental flask, a

member adapted to closely fit and telescope on

30 said base and to compress air therebetween,

and means carried by said telescoping mem-

ber for directing the compressed air into

40 said flask, said means having a sealing

element engageable with said supporting mem-

ber for confining the air. 100

45 19. A dental casting machine comprising

a base having a supporting member extend-

ing transversely thereof, means carried by

said member for supporting a dental flask, a

member adapted to closely fit and telescope

50 on said base and to compress air therebe-

tween, and means carried by said telescoping

55 member for directing the compressed air into

said flask, said means having sealing

elements engageable with said supporting

member and with the flask for confining the

air. 115

20. A dental casting machine comprising

a base having a supporting member extend-

ing transversely thereof, means carried by

said member for supporting a dental flask, a

member adapted to closely fit and telescope

60 on said base and to compress air therebe-

tween, and means carried by said telescoping

65 member for directing the compressed air into

said flask, said means having sealing

elements engageable with said supporting

member for directing the compressed air into

70 said flask, said means having a sealing ele-

ment engageable with said supporting mem-

ber for confining the air, and resilient means

for retaining said element in sealing positi-

75 21. A dental casting machine comprising

a base having a supporting member ex-

tending transversely thereof, means carried

by said member for supporting a dental flask, a member adapted to closely fit and

75 telescope on said base and to compress air

therebetween, means carried by said tele-

scoping member for directing the compressed

80 air into said flask, said means having seal-

ing elements engageable with said supporting

member and with the flask for confining the

air, and resilient means for retaining said

85 element in sealing position. 90

22. A dental casting machine comprising

a base having a supporting member extend-

ing transversely thereof, means carried by

said member for supporting a dental flask, a

bell shaped member adapted to closely fit and

90 telescope on said base and to compress air

therebetween, and means carried by said

telescoping member for directing the com-

pressed air into said flask. 95

23. A dental casting machine comprising

a base having a supporting member extend-

ing transversely thereof, means carried by

said member for supporting a dental flask, a

member adapted to telescope and closely fit

on said base and to compress air therebe-

20 tween, means carried by said telescoping

member for directing the compressed air

100 into said flask, and means for indicating the

air pressure in said member. 105

24. A dental casting machine comprising

a base adapted to support a dental flask, a

bell shaped member adapted to telescope on

105 said base and compress air therebetween and

supplemental air compressing means carried

by said member. 110

25. A dental casting machine comprising

a base adapted to support a dental flask, a

bell shaped member adapted to telescope on

115 said base and compress air therebetween,

supplemental air compressing means carried

by said member, and means for directing

the air to said flask. 120

26. A dental casting machine comprising

a base adapted to support a dental flask, a

bell shaped member adapted to telescope on

120 said base and compress air therebetween,

supplemental air compressing means mov-

ably carried by said member. 125

27. A dental casting machine comprising

a base adapted to support a dental flask, a

bell shaped member adapted to telescope on

130 said base and compress air therebetween,

and supplemental air compressing means in-

cluding a piston slidably carried by said

member. 135

28. A dental casting machine comprising

- a base adapted to support a dental flask, a bell shaped member adapted to telescope on said base and compress air therebetween, supplemental air compressing means mov-
5 ably carried by said member, and means for indicating the air pressure in said supplemental air compressing means.
29. A dental casting machine comprising a base adapted to support a dental flask, a bell shaped member adapted to telescope on said base and compress air therebetween, supplemental air compressing means includ-
10 ing a piston slidably carried by said mem-
ber, and means for indicating the air pres-
15 sure in said piston.
30. A dental casting machine comprising a base adapted to support a dental flask, and a bell shaped member adapted to telescope on said base, and compress air therebetween.
- 20 31. A dental casting machine comprising a base having means for supporting a dental flask, a vertically movable member adapted to telescope on said base and compress air within the member, a lever for actuating said vertically movable member and means for holding said lever in adjusted position after said member has been lowered to operative position.
32. A dental casting machine comprising
30 a base having means for supporting a dental flask, a vertically movable, hollow bell shaped member disposed above said base and adapted to receive heated air as the metal in the flask is melted and relatively movable
35 means carried by said member for directing the air downwardly into the flask as the bell shaped member is lowered to operative position.
33. A dental casting machine comprising
40 a pair of telescoping members, one of said members having a support for a dental flask and the other member having means for directing the air to said flask and increasing the velocity of the air as said members are
- moved into telescoping relation and the air 45 is compressed between the members.
34. A dental casting machine comprising a base having a support for a dental flask, a member adapted to telescope on said base, means slidably carried by and positioned 50 within said member for directing air into said flask as said member is moved to tele-
scoping position on said base, and means carried by said slidably means for increasing the air velocity as the air passes into the 55 flask.
35. A dental casting machine comprising a base having a support for a dental flask, a member adapted to telescope on said base, means slidably carried by and positioned 60 within said member for directing air into said flask as said member is moved to tele-
scoping position on said base, and means mounted in said slidably means for increasing the air velocity as the air passes into the 65 flask.
36. A dental casting machine comprising a pair of telescoping members, one of said members having a support for a dental flask and the other member having means for di-
recting the air to said flask as said mem-
70 bers are moved into telescoping relation and the air is compressed between the members, and flexible sealing means for sealing the adjacent surfaces of the telescoping mem-
75 bers when said members are disposed in telescoping relation.
37. A dental casting machine comprising a base having means for supporting a dental flask and means including a hollow, bell 80 shaped member adapted to telescope on said base for gradually applying air pressure to said flask and maintaining the pressure constant after the desired pressure has been reached.

In witness whereof, I have hereunto set my hand this 8th day of November, 1922.

MARTIN F. BURNS.
